UNITED STATES PATENT OFFICE.

JAMES FRANK LOBBETT, OF MIDDLEPORT, NEW YORK.

UNIVERSAL WORKHOLDER.

Application filed November 9, 1922. Serial No. 599,924.

To all whom it may concern:

Be it known that I, JAMES FRANK LOBBETT, a citizen of the United States of America, and a resident of Middleport, in the county of Niagara and State of New York, have invented a new and Improved Universal Workholder, of which the following is a description.

My invention relates to a work holder adapted to be secured to the cross slide of a lathe or to the table of a drill press or the like for holding work of various kinds in front of the spindle of the lathe or below the tool holder of the drill press.

15 The general object of my invention is to provide a work holder of the indicated character which may be readily secured in position and containing means for holding work of various kinds and adjusting the same to

20 various angular positions.

The nature of the invention and its distinguishing features and advantages will clearly appear as the description proceeds.

Reference is to be had to the accompanying drawings forming a part of this specification, it being understood that the drawings are merely illustrative of one example of the invention.

Figure 1 is a front elevation of my improved work holder in the position it occupies when applied to a lathe;

Figure 2 is a vertical section as indicated by the line 2—2, Figure 1;

Figure 3 is a horizontal section on the line 3—3, Figure 1, a portion of the flange of the angle frame being broken away;

Figure 4 is a plan view of the work holder applied to a lathe;

Figure 5 is an elevation of the work holder applied to the table of a drill press;

Figure 6 is a view similar to Figure 3 but showing a face plate as the work-holding means instead of the vise jaws.

In carrying out my invention in accordance with the illustrated example a frame 10 is provided of angle form or L-shape to present a laterally disposed flange or frame portion 11 formed with holes 12 for securing it as by bolts 13 to a cross slide A of a lathe B

50 or for employing it with the body of the frame 10 horizontally and the flange 11 vertically as in Figure 5 which includes an additional angle piece 110 secured by bolts 111 to the flange 11 and secured by bolts 112 to the table C of a drill press.

The body of the frame 10 extends beyond the flange 11 in the form of a depending extension 14.

A threaded spindle 15 is disposed centrally and longitudinally in the frame 10 turning in a bearing 16 in said frame in and positioned at what is the top of the frame when the work holder is secured to the lathe. The spindle 15 is held against longitudinal movement in any suitable manner as by collars 17, 18 at opposite sides of the bearing 16.

The numeral 19 indicates the body of a vise having on the back thereof lugs 20, 21 which project into a central opening 22 of frame 10 as clearly seen in Figure 2 to have guided movement in the frame 10 longitudinally of the opening 22. The spindle 15 extends freely through a bore in one lug 20 and has threaded engagement with the bore of the second lug 21 so that upon the spindle 75 being turned the vise body 19 will be caused to travel longitudinally along the spindle 15.

A cylindrical stud-like element 23 extends through the center of the vise body 19 between the lugs 20 and 21 and at the back of the frame 10 it receives a clamp plate 24 and a clamp nut 25. The threaded spindle 15 passes freely through a transverse bore in the stud 23 to permit the free turning of the spindle relatively to the stud 23 although 85 intersecting the latter. Said stud 23 moves with the vise body 19 in response to the turning of the threaded spindle 15.

The stud or cylindrical element 23 projects at its front end beyond the vise body 19 and has a round head 26 accommodated in a depression 127 of a turnable head 27 which may thus have movement about the axis of the stud 23 and its head 26 and relatively to the vise body 19. On the face of the head 27 are vise jaws 28 through which a threaded spindle 29 passes, said spindle having right and left threads to engage the respective jaws 28 so that the turning of the spindle in a given direction will cause the jaws 28 to approach each other or recede for the entrance or the removal of any work to be operated upon by the tool a in a lathe or a tool b in a drill press.

The spindle 29 has a reduced central portion 30 in a bearing 31, the face plate 32 of which is secured by screws 33 or the like, the arrangement being such that the spindle 30 and jaws 28 will turn with the head 27 about the stud 23 as an axis. The vise jaws 110

28 have lugs 35 diametrically disposed in opposite directions and adapted to be received in grooves 34 in the head 27.

It will thus be seen that the tool holder 5 is self-contained including its frame, the vise body 19 and head 27 with jaws 28 and their actuating spindle 29. The vise body 19 is adjustable along the spindle 15 and carries with it the head 27 and jaws 28 while the 10 head 27 with the jaws 28 thereon is turnable about the axis of the stud 28, whereby any desired position of the work in the jaws can be effected.

As shown in Figure 6 I may employ in 15 lieu of the vise jaws 28 a face plate 128 having outwardly disposed lugs 135 in opposite directions adapted to engage in the grooves 34.

I would state in conclusion that while 20 the illustrated example constitutes a practical embodiment of my invention, I do not limit myself strictly to the exact details herein illustrated, since, manifestly, the same can be considerably varied without 25 departure from the spirit of the invention as defined in the appended claims.

Having thus described my invention, I claim:

1. A work holder of the class described

comprising a frame having means to secure 30 it in position on a lathe, a drill press, or the like, and presenting in one member thereof a guideway, a vise body movable longitudinally along said guideway, actuating means for said body, a stud extending transversely through said frame member and through said vise body, means to slidably clamp said stud and vise body on the frame, a head swivelled on said stud, and work-holding jaws carried by said head. 35

2. A tool of the class described including a frame having a guideway, a vise body having spaced lugs extending into said guideway, a threaded spindle turnable in said frame, said spindle extending freely through one of said lugs and having threaded engagement with the other of said lugs, a stud through which said spindle extends, said stud passing through said vise body, means slidably clamping said vise body and stud 50 to said frame, a head swivelled on said stud at the front of said vise body to turn relatively to the latter and to slide with the said body in response to the turning of said spindle, and work-holding jaws carried by said head. 55

JAMES FRANK LOBBETT.
